CLOTHESLINE CLEANER AND PULLEY

Kolbjörn Olsen, Brooklyn, N. Y.

Application June 22, 1938, Serial No. 215,084

1 Claim. (Cl. 15—246)

My invention relates to improvements in cleaning devices for clotheslines and particularly to an improved clothesline pulley carrying said cleaning apparatus.

5 An important object of my invention is to provide a cleaning device which may be handled and sold as part of the pulley.

A further object of my invention is to provide a cleaning device which is easily renewable and 10 which is of simple and low cost construction. Other objects and advantages will be apparent during the course of the following description.

In the accompanying drawing, forming part of this specification, and in which like numerals are 15 employed to designate like parts throughout the same,

Figure 1 is a side elevation of a pulley containing the cleaning apparatus,

Figure 2 is an end elevation of the same,

Figure 3 represents a plan view,

Figure 4 is a side view of the cleaning bushing,

Figure 5 is an end view of the same,

Figure 6 represents a side view of the holding

clip, and,

25 Figure 7 is an end view of the same.

In the drawing, wherein for the purpose of illustration, is shown a preferred embodiment of

30 my invention, the numeral 10 designates the one-half of the pulley housing, and 11 is the other

half as illustrated in Figures 2 and 3. The said

pulley housing is preferably made from sheet

metal and is spot-welded at the edges 13, as

shown in Figure 2. The pulley housing contains

the pulley wheel 14 which is rotatable upon pivot

35 15, and at one end there is provided the usual

supporting clevis 16. At one end of the pulley

housing, where the rope 17 enters, the housing is

elongated and contains two slots, the lower or

inner edges of which are marked 18 and 19, re-

40 spectively, in Fig. 1. In these slots, or cut-outs,

are located the cleaning bushings 20 and 21 as

shown in Fig. 2. These bushings 20 and 21 are

split along one side 22 so that they may be slipped

over the line 17 from one side. Two spring clips

45 23 and 24 are placed over the said cleaning bush-

ings 20 and 21, respectively, to insure a firm even

pressure on the line. The spring clips 23 and 24

have small tabs 25 at each end to grip the felt

bushings 20 and 21 and keep same from sliding

50 with the line 17.

The operation of my invention is mostly obvious from the above description. After the line has been inserted in the pulley the felt bushings 20 and 21 are slipped over the line 17 in the slots 18 and 19 as indicated in Fig. 1. The bushings 20 and 21 are preferably made from felt, but any other suitable cleaning material may be used. These bushings are put on one from each side with the slot 22 in opposite directions so as to insure the cleaning of the entire line circumference. 10 When the spring clips 23 and 24 are placed over the bushings 20 and 21 these are held firmly and can not move out of slots 18 and 19. To insure cleaning of both ropes of a double clothesline it will be necessary to have two pulleys, one at each end of the line. It is obvious that only one cleaning bushing in each pulley may also be used if desired, but this would not give as good cleaning as the presently shown arrangement, and the additional cost of two bushings is very slight. 20

It is to be understood that the form of my invention, herewith shown and described, is to be taken as a preferred example of the same, and that various changes in the shape, size and arrangement of parts may be resorted to, without departing from the spirit of my invention, or the scope of the subjoined claim. 25

Having thus described my invention, I claim as new and desire to secure by Letters Patent of the United States:

30 In a device of the character described the combination of a pulley; a pulley housing, said housing completely enclosing the pulley but being open and extending away from same on the end where the clothesline enters and leaves, said housing having a slot transversely to and outside of the pulley and near the end where the clothesline enters the housing and extending along the direction of and in the path of said clothesline; a shaft journalling said pulley in the housing; a slit, cylindrical, fibrous bushing placed around the rope, in the slot in the housing, said bushing being of larger diameter than the width of the pulley and its length being approximately equal to the width of the slot in the housing, and a hairpin shaped spring clip placed transversely through said slot in the housing and over said fibrous bushing. 35 40 45 50
